PROTECTOR FOR TINNING CONNECTING RODS AND THE LIKE

William H. Bagley, Detroit, Mich., assignor to
Bohn Aluminum & Brass Corporation, Detroit,
Mich., a corporation of Michigan

Application July 20, 1931. Serial No. 551,997

3 Claims. (Cl. 91—12.2)

This invention relates to apparatus for tinning connecting rod bearings and the like and more especially to a protector or shield for use with apparatus of this character.

5 The invention finds particular utility in connection with the type of apparatus disclosed in application Serial No. 393,092 filed September 16, 1929.

In tinning connecting rod bearings and the like 10 with the type of apparatus illustrated in the aforesaid copending application, the two half bearings of a pair of connecting rods or other members to be tinned are simultaneously tinned by flowing through the opening formed by the two 15 half bearings, a column of molten tin. In practice it has been found that this molten tin spills or splashes onto the body of the connecting rod and not only tends to raise the temperature of the body of the rod to the point where the effects 20 of the previous heat treatment is destroyed, but also this tin which adheres to the body of the connecting rod must subsequently be removed.

It is therefore the object of this invention to provide a shield or protector which may be quickly 25 brought into position to shield the body of the connecting rod or rods while the bearing portions thereof are being tinned.

The several objects, advantages and novel details of construction of this invention will be 30 made more apparent as this description proceeds, especially when considered in connection with the accompanying drawings, wherein

Figure 1 is a front elevational view of a tinning machine constructed in accordance with this invention showing my improved protector or shield associated therewith;

Figure 2 is a fragmentary vertical sectional view on a larger scale, of the lower portion of the machine;

40 Figure 3 is a fragmentary elevational view taken substantially on the plane indicated by line 3—3 in Figure 2;

Figure 4 is a transverse sectional view taken substantially on the plane indicated by line 4—4 45 in Figure 3;

Figure 5 is a bottom plan view of one of the shield members, and

Figure 6 is a perspective view of one of the shield or protector members.

50 Referring now to the drawings and more especially to Figures 1 and 2 it will be noted that the tinning machine comprises essentially a base 10 in which a pot or container 11 is arranged, this pot containing the tinning metal.

55 An upright frame member 12 is provided with

bearings 13 to support a main shaft 14 upon the end of which is mounted a brush 15. The shaft 14 is rotated to rotate the brush 15 and means is provided, such as a lever 16, to raise and lower the brush. When the brush is rotated it is lowered to project the same into the bearing opening so as to brush the surface being tinned during the tinning operation.

The reference character 17 indicates a pump shaft which actuates the propeller blades 18 of a 65 pump arranged in the pot 11. The pump is of the centrifugal type, the blades 18 rotating in a pump chamber 19 which communicates with a substantially tangential passageway 20 which in turn connects with an upwardly extending 70 spout or passageway 21.

By properly regulating the speed of the pump, a column of molten metal can be projected a predetermined distance above the upper end of the 75 spout 21.

Mounted upon the flange 22 of the spout 21 is a fixture plate 23 for holding the connecting rods to be tinned. This fixture plate is pivotally mounted as at 24 to the flange 22 and is provided with a handle 25 by means of which the fixture plate may be swung about its pivot 24. The fixture plate is provided with an enlargement or extension 26 which acts as a cover for the upper end of spout 21 when the fixture plate is moved to the loading position, in which position the connecting rod is fixed thereon. In the other position of the fixture plate an opening 27 formed therein registers with the spout 21, the two half bearing portions of the connecting rods being disposed over this aperture in the fixture 85 plate to thus bring them into registration with the spout.

The fixture plate is usually provided with a circular depression 28 in which the bearing portions B of the connecting rod C are located. The 95 fixture plate is provided with oppositely extending hook-like clips or abutments 29 so that the double connecting rod may be placed upon the fixture plate and then rotated about its center to locate the ends of the double connecting rod 100 under these clips. Thus the connecting rod may be readily attached to the fixture plate and may as readily be removed.

The structure thus described constitutes the 105 essentials of a tinning apparatus of the character with which my improved shield or guard may be employed. When the column of tin is projected up through the spout 21, it flows in contact with the bearing surfaces B of the double connecting rod and spills up over the edge 110.

thereof and in practice this excess tin flows back down into the pot 11. However, a considerable amount of this tin spills onto the body portions of the connecting rods and it is to eliminate this objection that the present invention was designed.

By reference particularly to Figures 3, 4, 5 and 6 it will be noted that my improved shield or guard comprises a pair of sections each designated generally by the reference character 30, each of which comprises a rearwardly extending lug or ear 31 by means of which the shield section is pivotally mounted to the fixture plate 23 as indicated at 32. Each shield section has a portion 33 adapted to fit over the body of the connecting rod and to thus shield the same from the spilled molten metal. Extending forwardly from each section 33 is an arm 34 which is preferably weighted as at 35. A depending lug 36 is provided so that the two sections of the complete shield or guard can be united by a rod or the like 37 which may be grasped by the operator to swing the pair of shield sections upwardly about the pivots 32. The shield sections are thus raised when a double connecting rod is to be attached to the fixture plate and the shield sections are then swung down to the position illustrated in Figure 3 to cover the body portions of the connecting rods, the shield being held in this operative position, against accidental displacement, by the weights 35. It will thus be seen that such molten tin or other metal which spills up over the bearing surfaces B will contact with the shield sections 30 and not with the bodies of the connecting rods so that the body portions will be kept free from contact with the tinning metal.

Obvious modifications will suggest themselves to those skilled in this art and to this end reser-

vation is made to make such changes as may come within the purview of the accompanying claims.

What I claim as my invention is:

1. In an apparatus of the class described, means for producing and maintaining a free column of molten tinning metal, a support for a connecting rod or the like for holding the bearing portions of the same in the path of said column, and a protector for the body of the connecting rod comprising a shield member pivotally mounted on said support and having a portion substantially enclosing the body of said connecting rod, and means for holding said shield against accidental displacement when in operative position. 80

2. In an apparatus of the class described, means for producing and maintaining a free column of molten tinning metal, a support for a connecting rod or the like for holding the bearing portions of the same in the path of said column, a pivotally supported shield cooperating with said support for substantially enclosing the portion of the connecting rod adjacent the portion being tinned, and a weight on said shield 85 90 95 acting to hold the same in operative position.

3. In an apparatus of the class described, means for producing and maintaining a free column of molten tinning metal, a support for a connecting rod or the like for holding the bearing portions of the same in the path of said column, a pair of shield sections cooperating with said support for substantially enclosing the portions of the connecting rod adjacent the portion being tinned, and means connecting said shield sections so that they may be operated together. 100 105 110 115
